UNITED STATES PATENT OFFICE.

MICHAEL PETROCCHI, OF GRAND RAPIDS, MICHIGAN, ASSIGNOR TO ROSE PATCH & LABEL COMPANY, OF GRAND RAPIDS, MICHIGAN, A CORPORATION OF MICHIGAN.

LABEL CUTTING AND FOLDING MACHINE.

1,211,489

Specification of Letters Patent.

Patented Jan. 9, 1917.

Application filed November 25, 1914. Serial No. 873,885.

To all whom it may concern:

Be it known that I, MICHAEL PETROCCHI, a citizen of the United States, residing at Grand Rapids, in the county of Kent and State of Michigan, have invented new and useful Improvements in Label Cutting and Folding Machines, of which the following is a specification.

The present invention relates to label cutting and folding machines; and its object is to provide a new and improved machine of that character, which shall be simple and economical in construction, and rapid and effective in operation; and further, to provide new and improved folding devices for the labels; and further, to provide new and improved feeding devices for such machines; and further, to provide new and improved creasing devices for the folded labels; and further, to provide other new and improved features and devices in such machines, and improved economical constructions, appearing hereinafter.

By these machines, labels for clothing and the like are cut from a label strip into label-lengths which are then folded at the cutoff ends; whereupon, they may be sewed or otherwise secured to the articles to be labeled.

The objects of this invention are attained by, and the invention finds a preferable embodiment in, the structure hereinafter described and illustrated in the accompanying drawings, in which:

Figure 1 is a side elevation of a label cutting and folding machine; Fig. 2 is a rear elevation thereof; Fig. 3 is a top plan view of the same; Fig. 4 is a front view thereof; Figs. 5 and 6 are fragmentary vertical sections of the same on a plane corresponding with line A—B of Fig. 3, and showing certain parts in different positions; Fig. 7 is a bottom plan view of a folded label; Figs. 8 and 9 are vertical sections of said machine on planes corresponding with line C—D of Fig. 2 and showing certain parts in different positions; Fig. 10 is a detail side view of the cutter and its operating parts; Fig. 11 is a fragmentary detail side view of a label strip and a feeding device therefor; Fig. 12 is a fragmentary face view of a label strip; Fig. 13 is a detail fragmentary vertical transverse sectional view of a tilting table with connected parts; Fig. 14 is a

detail top plan view of a feeding device 55 for a label strip, a part of the upper jaw of such device being broken away; Fig. 15 is a side view of said feeding device; Fig. 16 is a detail fragmentary vertical section of a movable bearing-block for a creasing roll, 60 and adjusting means, on a plane corresponding with a line E—F of Fig. 2; Fig. 17 is a detail fragmentary view of certain operating parts; and Fig. 18 is a top plan view of a feeding device for a label strip with guide 65 members therefor.

In that embodiment of the invention chosen for illustration in the accompanying drawings and for particular description herein, a suitable frame 1 supports the movable or operating parts, which are driven by the pulley 2. From a rotatable reel 3 may be unwound the label strip 4, its face 5 (i.e., its label-displaying side) downward, by the feed 6 reciprocated by means of a lever 7 oscillated by a cam 8 on the shaft 9 which is rotated by the driving shaft through suitable gears 10. This feed 6 has a jaw 11 spring-pressed at 12 into frictional feeding engagement with the label strip, 80 and has also guide members 12' adapted to engage the edges of the label strip (as shown in Fig. 18) and adjustable as by the set-screws 13 passing through the slots 14, to accommodate the device to label strips of 85 different widths. Another form of guide may be employed, comprising the guide bar 15 adjustable by a thumb screw 16 passing through a slot 17, as shown in Fig. 3.

A label-length 18 of the label strip being 90 fed between the separated clamping jaws 19 and 20 of the vertically movable label-length holding member 21 of the label folder, the upper jaw 19 is forced downward (to clamp or hold the label-length) by 95 the bell-crank lever 22 whose arm 23 (provided with an anti-friction roller 24) engages a notch 25 in a slide 26 which carries said upper jaw: This bell-crank lever is actuated by the cam-groove 27 in which 100 travels the arm 28 of said lever (furnished with an anti-friction roller 29), the groove being located in the face of a disk 30 carried by the shaft 9. The label-length being thus securely held between the clamping jaws of 105 the label-length holding member of the label folder, the feed 6, which has now ceased its feeding movement, acts as a strip-re

taining device to retain the label strip against movement toward the label-length holding member, thus holding the strip in such position that the label-length may be severed from the rest of the label strip by a clean straight cut between such feed and said holding member. This feed is retracted to the position for its next feeding movement by its spring 31, whose outer end is anchored on the hook 32: the cutting operation may be timed to occur after the retracting movement of this feed begins, whereby, (the label-length being securely held by the clamping jaws 19 and 20, and the feed's jaw 11 being at all times in merely frictional engagement with the label strip), this feed in its retraction slips along the strip frictionally and acts as a strip-tautening device, so that the strip is not only merely held at each side of the line of cutting, but is tautened to effect an even more perfect, clean and straight cutting thereof. The cutter comprises a fixed shear blade 33 and a pivotally-mounted coöperating shear-blade 34 closed and opened by the pins 35 and 36 respectively of the slide 26 engaging the lever arm 37 of said movable blade.

The label-length being now severed from the rest of the label strip, it with the entire holding member 21, is carried downward against the pressure of a spring 38 by the continued movement of the bell-crank lever 22, and each of the label-length's ends extending beyond the outer edges of the fold-form 39 which is carried by and projects horizontally from the upper jaw 19, is brought into engagement with the inclined face 40 of a folding member 41, there being thus a relative movement of the label-length holding member 21 and this member 41 in the direction of the plane of the label length. This folding member 41 being yieldingly held in its coöperating engagement by a suitable spring 42 is moved horizontally against said spring and away from the label-length holder by the latter's downward travel, thus bending the end of the label-length upwardly; until at the end of the label-length's holder's downward travel, its fold-form 39 is brought into registration with a coöperating fold-form 43 at the end of the folding member's face 40, whereupon said spring 42 moves the folding member toward the label-length holding member and folds the end of the label-length between the fold-forms and into parallel relation with the label-length's face. The label-length holding member 21 and the folding member 41 thus coöperate to form a label folder. The adjectives vertical, horizontal, etc., are relative rather than absolute, as used herein. After their folding coöperation, these members 21 and 41 are separated to disengage their fold-forms by a lever 44, one of whose arms 45 (carrying an anti-friction roller 46)

engages a notch 47 in the folding member's side, the other arm 48 of said lever (carrying an anti-friction roller 49) being actuated by a rotating cam 50 on the shaft 9. A pair of these movable folding members 41 with actuating means, etc., are provided as shown, one for each end of the label-length.

The clamping jaws 19 and 20 are now separated to permit the expulsion of the folded label-length from its holding member 21, and such label-length is thereupon so expelled in a direction parallel with its fold by an expeller 51 having upwardly and inwardly turned flanges 52 embracing the edges of the fold-form 39. This expeller is thus slidable along said fold form and is adapted to abut against the adjacent edge of the folded label-length and push it along said fold-form and into the engagement of rolls 53 and 54, and without unfolding or disturbing such folds. The fold-form 39 near its extremity next to these rolls and beyond the coöperating action of the other fold-form therewith, may be gradually increased in width as shown at 69 and decreased in thickness to take up the bight in the folds caused by the thickness of the fold-form. The clamping jaws are separated and the expeller is thereupon operated to expel the folded label-length, by a lever 55 fulcrumed at 66 and oscillated by a crank arm 56 having an anti-friction roller 57 and carried by the shaft 9; this crank arm during a portion of its rotation engages a swinging lever arm 58 which engages and moves an arm 59 of said lever 55, the other arm 60 whereof carries a roll 61 which engages an inclined rib or track 62 on the lower clamping jaw 20 and by said movement of the lever 55 forces such lower jaw downward against the pressure of its spring 38; whereupon, the said movement of the lever 55 continuing, its anti-friction roller 63, engaging in a notch 64 in the expeller, slides it along the fold-form 39 to expel the label-length. These operations are illustrated in Figs. 8 and 9. As the crank arm 56 is turned to a position permitting a reverse movement of the lever 55, the spring 38 raises the lower clamping jaw 20, which movement slides the roller 61 backward and off from the inclined rib 62, and the expeller is also retracted. The lower jaw's upward movement is arrested by a stop 65, as shown in Fig. 8; thereupon the bell-crank lever 22 raises the upper clamping jaw 19 farther, thus opening the jaws for the reception of another label-length.

The label strip feed 6 (hereinbefore described) is auxiliary to a pulling feed for such strip. This pulling feed comprises a pair of pivotally connected fingers 67 and 68 adapted to be moved between the open clamping jaws 19 and 20 into operatively engaging position with the label strip (al-

ready fed into such position by the auxiliary feed 6) and to be moved reversely to pull a label-length into its position to be held by said clamping jaws of the label-length holding member 21. This pulling feed is reciprocated between the open clamping jaws by a lever 70, one of whose arms (having an anti-friction roller 71) engages in a notch 72 in the feed, and whose other arm (having 75 a similar roller 73) travels in an actuating cam groove 74 in a disk 75 carried by the shaft 9. The fingers 67 and 68 are pressed into feeding engagement with the label strip by a suitable spring 76, and they are opened 10 to receive the label-length by the following mechanism: When this feed is moved to the end of its outward travel (its position shown in Fig. 5), a portion 77 of the upper clamping jaw 19 in its descending movement engages a lever 78 (having the anti-friction roller 79) and through its adjusting screw 80 moves a lever arm 81 (against the pressure of its spring 82) into engagement with the arm 83 of the upper finger 67, and thus 15 opens the fingers and disengages them from the label-length; immediately the fingers are opened, a catch 84 pivoted on the lower finger 68 is pressed (by its spring 85) below a roller 86 carried by the upper finger 67 and thus holds the fingers open, in which condition they remain until this feed is moved 20 into position to engage another label-length, whereupon the catch is turned out of engagement with the roller 86 by striking a stop 87, (whose position is adjustable by a screw rod 88), and thereupon the fingers are pressed by their spring 76 to engage the label-length. This construction is particularly shown in Figs. 14 and 15. When the 25 label-holding member 21 descends with the cut-off label-length held in its clamping jaws 19 and 20, such label-length (if of ordinarily-constructed material) may be by such descending movement pulled out from 30 the engagement of the fingers without first separating the same; but where the length of the label-lengths is fixed (as shown in Fig. 11) by a rib 113 raised above the surface of the label strip, the fingers 67 and 68 35 may be adjusted, as by a screw 114 (shown in said figure) to slide along the opposite surfaces of the strip and to holdingly engage such ribs only; by this arrangement the cutting of the label-lengths is invariable relation to such ribs and any printed matter, etc., displayed on the label-lengths is assured.

Coöoperating creasing rolls 53 and 54 rotated by intermeshing gears 91 and 92 on 40 their respective shafts, and driven by the shaft 89 through its gear 93, receive the folded label-length from the fold-form 39 through the action of the expeller 51. The folds of the label-length are creased or 45 pressed down flat on the body of the label-length between these rolls, which are yieldingly pressed toward each other by springs 94 located between the movable bearing blocks 95 of the upper roll 53 and screws 96 for adjusting the tension of such springs. 70 These creasing rolls deliver the label to a belt-conveyer 97 mounted on rolls 98 and 99 driven by belts 100 and 101 from the power shaft. This belt-conveyer delivers the label to a tilting table 102 pivoted at 103 and tilted by a connecting rod 104 pivoted to a bell-crank lever 105 which is actuated by the crank arm 56 against the pressure of a spring 106. The tilting of the table 102 deposits the label on a second belt conveyer 107 mounted on rolls 108 and 109 and driven as shown. This second belt-conveyer delivers the label to a third belt-conveyer 110 (shown in Fig. 1) driven in the opposite direction as by a belt 115 indicated in Fig. 1, 80 and mounted on rolls 111 and 112. These oppositely traveling belt-conveyers 107 and 110 turn the label over, as particularly shown in Fig. 1. The roll 116 (coöperating with roll 112) may be heated in any suitable and well-known manner whereby the folded label 85 is ironed thereby. 90

An additional guide 117 for the label strip having a hinged member 118 adapted to fold down over the surface of the strip is 95 shown in Figs. 2 and 3; and an arm or striker 119 adapted to operate counting mechanism (not shown) appears in Fig. 3, carried by the label-length holding member.

The label-strip 4 is shown with side folds 100 120, which are formed thereon before subjecting the strip to the action of my machine. Such label-strips are particularly adapted for the making of patches for garments, etc. Where the strip is woven with a 105 selvage along its edges, such side folds 120 are of course, unnecessary.

I have described this embodiment of my invention very minutely; said invention may, without departing from the invention, be 110 embodied in other forms varying greatly from that shown and described.

I claim:

1. In an automatic label cutting and folding means, the combination of a frame, a 115 label feeding means comprising grippers adapted to grip the end of a label strip and advance the same, a label strip tautening means coöperating with said grippers, a label length holder adapted to receive the 120 label length comprising separable jaws and having a fold form, automatic cut off means for severing a label length from the label strip after the same has been forwarded into the label holder, coöperating folding members in movable relation to the said label length holder, movable in the relative direction of the plane of the label length and having inclined faces to coöperate with the fold form and to fold the ends of the label, means 130

- for moving the said holder and folder in relation to each other, means for separating the members of said holder and folding means after the folding operation, an expeller adapted to expel the folded label length and deliver the same from the folder, creasing rolls disposed to receive the expelled label length, a belt conveyer adapted to receive the label from the creasing rolls, 5 a tilting table coöperating with said conveyer, a second belt conveyer to receive the label from the tilting table, a third belt conveyer driven in opposite direction to the said second belt conveyer to receive the label therefrom and thus turn the label over, and creasing rollers to receive the label length from the third belt and discharge it from the machine.
2. In an automatic label cutting and folding means, the combination of a frame, a label feeding means comprising grippers adapted to grip the end of a label strip and advance the same, a label strip tautening means coöperating with said grippers, a label length holder adapted to receive the label length comprising separable jaws and having a fold form, automatic cut off means for severing a label length from the label strip after the same has been forwarded into the label holder, coöperating folding members in movable relation to the said label length holder, movable in the relative direction of the plane of the label length to coöperate with the fold form and to fold the ends of the label, means for moving the said holder and folder in relation to each other, means for separating the members of said holder and folding means after the folding operation, and means to expel the said label.
3. In an automatic label cutting and folding means, the combination of a frame, a label feeding means comprising grippers adapted to grip the end of a label strip and advance the same, a label strip tautening means coöperating with said grippers, a label length holder adapted to receive the label length comprising separable jaws and having a fold form, automatic cut off means for severing a label length from the label strip after the same has been forwarded into the label holder, coöperating folding members in movable relation to the said label length holder, movable in the relative direction of the plane of the label length to coöperate with the fold form and to fold the ends of the label, means for moving the said holder and folder in relation to each other, means for separating the members of said holder and folding means after the folding operation, and means to expel the said label.
4. In an automatic label cutting and folding means, the combination of a frame, a label length holder adapted to receive the label length comprising separable jaws and having a fold form, coöperating folding members in movable relation to the said label length holder, movable in the relative direction of the plane of the label length to coöperate with the fold form and to fold the ends of the label, means for moving the said holder and folder in relation to each other, means for separating the members of said holder and folding means after the folding operation, and means to expel the said label.
5. In an automatic label cutting and folding means, the combination of a frame, a label length holder adapted to receive the label length comprising separable jaws and having a fold form, coöperating folding members in movable relation to the said label length holder, movable in the relative direction of the plane of the label length and having downwardly and inwardly inclined faces to coöperate with the fold form and to fold the ends of the label, means for moving the said holder and folder in relation to each other, means for separating the members of said holder and folding means after the folding operation, and means to expel the said label.
6. In an automatic label cutting and folding means, the combination of a frame, means for automatically folding the edges of the label length, an expeller adapted to expel the folded label length and deliver the same from the folder, creasing rolls disposed to receive the expelled label length, a belt conveyer adapted to receive the label from the creasing rolls, a tilting table coöperating with said conveyer, a second belt conveyer to receive the label from the tilting table, a third belt conveyer driven in opposite direction to the said second belt conveyer to receive the label therefrom and thus turn the label over, and creasing rolls to receive the label length from the third belt and discharge it from the machine.
7. In an automatic label folding machine of the character described, a suitable frame;

- and a label folder comprising a label-length holding member and a laterally yielding folding member yieldingly held in coöperating relation with the first member.
8. In a machine of the character described, a suitable frame; a label folder comprising a label-length holding member and a folding member having a laterally yielding inclined face yieldingly held in coöperating relation with the first member, said members being interrelatively movable to fold the end portion of the label-length by the relative movements of said members.
9. In a machine of the character described, the combination of a suitable frame; a label folder comprising a vertically movable label-length holding member having a fold-form, a horizontally movable folding member having a downwardly and inwardly inclined face terminating in a fold-form complementary with the first fold-form and yieldingly held in coöperating relation with the first member, the members being adapted to fold the end portion of the label-length by the relative movement of said members; and means for separating said members after their folding coöperation; coacting for the purpose specified.
10. In an automatic label folding machine of the character described, the combination of a suitable frame; a label folder comprising vertically movable label-length holding jaws having a fold-form, a movable folding member having means for turning the ends of the label length upwardly as the folding member moves away from the fold-form.
11. In an automatic label folding machine of the character described, the combination of a suitable frame; a label-folder comprising label-length holding jaws and a coöperating folding member in movable relation thereto, such movement being in the direction of the plane of the label length; and a feed adapted to feed a label strip to the holding jaws; means for severing said label coacting for the purpose specified.
12. In an automatic label cutting and folding machine of the character described, the combination of a suitable frame; a label folder comprising label-length holding jaws and a coöperating folding member in movable relation thereto, such movement being in the direction of the plane of the label length; a feed adapted to feed a label strip to the holding jaws; and a cutter adapted to sever the label-length from the strip; coacting for the purpose specified.
13. In a machine of the character described, the combination of a suitable frame; a label folder comprising a label-length holding member, a folding member coöperating therewith, and means for moving one said member relatively to the other in a direction transverse to the label-length's face; a strip- tautening device adapted to engage and 65 tauten a label strip of which the label-length is a portion and movable toward and from the label-length holding member; and a cutter adapted to sever the label-length from the label strip between the label-length holding member and said device; coacting for the purpose specified.
14. In a machine of the character described, the combination of a suitable frame; a label folder comprising a label-length holding member, a folding member coöperating therewith, and means for moving one said member relatively to the other in a direction transverse to the label-length's face; a feeding and retaining device for a label strip of 75 which the label-length is a portion; and a cutter adapted to sever the label-length from the label strip between the label-length holding member and said device; coacting for the purpose specified.
15. In a machine of the character described, the combination of a suitable frame; a label folder comprising a label-length holding member, a folding member coöperating therewith, and means for moving one said member relatively to the other in a direction transverse to the label-length's face; a feeding and tautening device for a label strip of 80 which the label-length is a portion, adapted to feed the label strip toward the label-length holding member and to engage the strip when the label-length is held in the label-length holding member and to be retracted from said member to tauten the strip; and a cutter adapted to sever the label-length from the label strip between the label-length holding member and the said device; coacting for the purpose specified.
16. In an automatic label folding machine of the character described, the combination 105 of a suitable frame; a label folder comprising label-length holding clamping jaws, and a folding member coöperating with said holding member, said members being relatively movable in the direction of the plane of the label length; a pulling feed for a label strip of which the label-length is a portion adapted to be moved between the open jaws into operative engagement with the label strip and reversely to pull the label-length into its position to be clamped by the jaws; coacting for the purpose specified.
17. In an automatic label cutting and folding machine of the character described, the combination of a suitable frame; a label 110 folder comprising label-length holding clamping jaws, and a folding member coöperating with said holding member, said members being relatively movable in the direction of the plane of the label length; a pulling feed for a label strip of which the label-length is a portion adapted to be moved between the open jaws into operative

engagement with the label strip and reversely to pull the label-length into its position to be clamped by the jaws; and a cutter adapted to sever the label-length from the strip; coacting for the purpose specified.

18. In a machine of the character described, the combination of a suitable frame; a label folder comprising a label-length holding member having separable clamping jaws, and a folding member coöperating with said holding member, said members being relatively movable in the direction of the plane of the label-length; a pulling feed for a label strip of which the label-length is a portion adapted to be moved between the open jaws into operative engagement with the label strip and reversely to pull the label-length into its position to be clamped by the jaws; and an auxiliary feed adapted to feed the label strip to the pulling feed's engaging position therewith; coacting for the purpose specified.

19. In a machine of the character described, the combination of a suitable frame; a label folder comprising a label-length holding member having separable clamping jaws, and a folding member coöperating with said holding member, said members being relatively movable in the direction of the plane of the label-length; a pulling feed for a label strip of which the label-length is a portion adapted to be moved between the open jaws into operative engagement with the label strip and reversely to pull the label-length into its position to be clamped by the jaws; an auxiliary feed adapted to feed the label strip to the pulling feed's engaging position therewith; and a cutter adapted to sever the label-length from the strip between the auxiliary feed and the label-length holder; coacting for the purpose specified.

20. In an automatic label folding machine of the character described, the combination of a suitable frame; a label folder comprising label-length holding clamping jaws, and a folding member coöperating with said holding member, said members being relatively movable in the direction of the plane of the label-length; a pulling feed for a label strip of which the label-length is a portion with engaging jaws adapted to be moved along the strip into operative engagement with a projection on the surface thereof to pull by said projection the label-length into position to be cut and folded; and means for releasing the feed from said projection; coacting for the purpose specified.

21. In an automatic label cutting and folding machine of the character described, the combination of a suitable frame; a label folder comprising label-length holding clamping jaws; and a folding member coöperating with said holding member, said members being relatively movable in the

direction of the plane of the label-length; a pulling feed for a label strip of which the label-length is a portion with engaging jaws adapted to be moved along the strip into operative engagement with a projection on the surface thereof to pull by said projection the label-length into position to be cut and folded; means for releasing the feed from said projection; and a cutter adapted to sever the label-length from the strip; coacting for the purpose specified.

22. In an automatic label folding machine of the character described, the combination of a suitable frame; a label folder comprising label-length holding clamping jaws, and a folding member coöperating with said holding member, said members being relatively movable in the direction of the plane of the label-length; a pulling feed for a label strip of which the label-length is a portion adapted to be moved between the open jaws into operative engagement with the label strip and reversely to pull the label-length into its position to be clamped by the jaws; and means for releasing the feed from its engagement with the strip; coacting for the purpose specified.

23. In an automatic label cutting and folding machine of the character described, the combination of a suitable frame; a label folder comprising label-length holding clamping jaws; and a folding member coöperating with said holding member, said members being relatively movable in the direction of the plane of the label-length; a pulling feed for a label strip of which the label-length is a portion adapted to be moved between the open jaws into operative engagement with the label strip and reversely to pull the label-length into its position to be clamped by the jaws; means for releasing the feed from its engagement with the strip; and a cutter adapted to sever the label-length from the strip; coacting for the purpose specified.

24. In a machine of the character described, the combination of a suitable frame; a label folder comprising a vertically movable label-length folding member having a fold-form, and a horizontally movable folding member having an inclined face terminating in a fold-form corresponding with the first fold-form and yieldingly held in co-operating relation with the first member, the members being adapted to fold the end portion of the label-length by the relative movement of said members; means for separating said members after their folding coöperation; and an expeller adapted to expel the folded label-length in the direction parallel with its fold line from the holding member; coacting for the purpose specified.

25. In a machine of the character described, the combination of a suitable frame; a label folder comprising a label-length

- holding member and a cooperating folding member in movable relation thereto in the direction of the plane of the label length; a cutter adapted to sever the label-length from a label strip; and an expeller adapted to expel the folded label-length in the direction parallel with its fold line from the holding member; coacting for the purpose specified.
26. In a machine of the character described, the combination of a suitable frame; a label folder comprising a vertically-movable label-length holding member having a fold-form, and a horizontally movable folding member having a corresponding fold-form, the members being adapted to fold the end portion of the label-length by the relative movement of said members; a cutter adapted to sever the label-length from a label strip; means for separating said members after their folding coöperation; and an expeller adapted to expel the folded label-length in the direction parallel with its fold line from the holding member; coacting for the purpose specified.
27. In a machine of the character described, the combination of a suitable frame; a label folder comprising a vertically-movable label-length holding member having a fold-form, and a horizontally movable folding member having an inclined face terminating in a fold-form corresponding with the first fold-form and yieldingly held in co-operating relation with the first member, the members being adapted to fold the end portion of the label-length by the relative movement of said members; a cutter adapted to sever the label-length from a label strip; means for separating said members after their folding coöperation; and an expeller adapted to expel the folded label-length in the direction parallel with its fold line from the holding member; coacting for the purpose specified.
28. In a machine of the character described, the combination of a suitable frame; a label folder comprising a vertically-movable label-length holding member having separable clamping jaws and a fold-form, and a horizontally movable folding member having an inclined face terminating in a fold-form corresponding with the first fold-form and yieldingly held in co-operating relation with the first member, the members being adapted to fold the end portion of the label-length by the relative movement of said members; means for opening the jaws to release the folded label-length; means for separating said members after their folding coöperation; and an expeller adapted to expel the folded label-length in the direction parallel with its fold line from the holding member; coacting for the purpose specified.
29. In a machine of the character described, the combination of a suitable frame; a label folder comprising a label-length hold-
- ing member and a coöperating folding member in movable relation thereto in the direction of the plane of the label length; a feed adapted to feed to the holding member a label strip of which the label-length is a portion; and an expeller adapted to expel the folded label-length in the direction parallel with its fold line from the holding member; coacting for the purpose specified.
30. In a machine of the character described, the combination of a suitable frame; a label folder comprising a vertically-movable label-length holding member having a fold-form, and a horizontally movable folding member having a corresponding fold-form, the members being adapted to fold the end portion of the label-length by the relative movement of said members; a feed adapted to feed to the holding member a label-strip of which the label-length is a portion; means for separating said members after their folding coöperation; and an expeller adapted to expel the folded label-length in the direction parallel with its fold line from the holding member; coacting for the purpose specified.
31. In a machine of the character described, the combination of a suitable frame; a label folder comprising a vertically-movable label-length holding member having a fold-form, and a horizontally movable folding member having an inclined face terminating in a fold-form corresponding with the first fold-form and yieldingly held in co-operating relation with the first member, the members being adapted to fold the end portion of the label-length by the relative movement of said members; a feed adapted to feed a label-strip of which the label-length is a portion; means for separating said members after their folding coöperation; and an expeller adapted to expel the folded label-length in the direction parallel with its fold line from the holding member; coacting for the purpose specified.
32. In a machine of the character described, the combination of a suitable frame; a label folder comprising a label-length holding member having a fold-form and a folding member having an inclined face terminating in a fold-form corresponding with the first fold-form and yieldingly held in co-operating relation with the first member, said members being relatively movable in the direction of the plane of the label length and being adapted to fold the end portion of the label-length by the relative movement of said members; and creasing rolls for creasing the folded label-length; coacting for the purpose specified.
33. In a machine of the character described, the combination of a suitable frame; a label folder comprising a vertically-movable label-length holding member having a fold-form, a horizontally movable folding

- 8
- member having an inclined face terminating in a fold-form corresponding with the first fold-form and yieldingly held in coöperating relation with the first member, the 5 members being adapted to fold the end portion of the label-length by the relative movement of said members; means for separating said members after their folding coöperation; and creasing rolls for creasing the 10 folded label-length; coacting for the purpose specified.
34. In a machine of the character described, the combination of a suitable frame; a label folder comprising a vertically movable label-length holding member having a 15 fold-form, a horizontally movable folding member having a fold-form corresponding with the first fold form, the members being adapted to fold the end portion of the label-length by the relative movement of said 20 members; means for separating said members after their folding coöperation; and creasing rolls for creasing the folded label-length; coacting for the purpose specified.
35. In a machine of the character described, the combination of a suitable frame; a label folder comprising label-length holding jaws, a member coöperating therewith, and means for moving one of said devices 25 relatively to the other in a direction transverse to the label-length's face; a cutter adapted to sever the label-length from the label strip; and creasing rolls for creasing the folded label-length; coacting for the 30 purpose specified.
36. In a machine of the character described, the combination of a suitable frame; a label folder comprising label-length holding jaws, a folding member coöperating 35 therewith, and means for moving one of said devices relatively to the other in a direction transverse to the label-length's face; a feed adapted to feed a label strip to the holding 40 jaws; a cutter adapted to sever the label-length from the label strip; and creasing rolls for creasing the folded label-length; coacting for the 45 purpose specified.
37. In a machine of the character described, the combination of means for folding the end portion of a label-length; creasing rolls for creasing the folded label; means 50 for turning the label over; and other creasing rolls for again creasing the folded label after being turned over; coacting for the 55 purpose specified.
38. In a machine of the character de-
- scribed, the combination of means for folding the end portion of a label-length; creasing rolls for creasing the folded label; a belt-conveyer adapted to receive the label from the rolls; a tilting table adapted to receive the label from said conveyer; a second belt-conveyer adapted to receive the label from the tilting table; a third belt-conveyer driven in a direction opposite the 60 second belt-conveyer and adapted to receive the label from the second belt-conveyer and to turn the label over; and other creasing rolls adapted to receive the label from the third belt-conveyer and to again crease the 65 folded label after its being turned over; coacting for the purpose specified.
39. In a machine of the character described, a suitable frame; and a label folder comprising a label-length holding member 70 having a fold-form and a coöperating folding member in movable relation to said holding member in the direction of the plane of the label length and having a fold-form coöperating with the first fold form, the fold 75 forms being adapted to fold the end portion of the label-length by the relative movement of the members, one of the fold-forms being near its extremity gradually increased in width, and means for withdrawing the 80 folded label over the widened end of said last named fold-form.
40. In an automatic label cutting and folding means, the combination of a frame, a label strip feeding means, a label length 85 holder means adapted to grasp a label length at the end of the label strip, comprising separable jaws, one of said jaws constituting a fold form, means to cut off said label length while embraced by said jaws, folding 90 members coöperating with said fold form disposed to deflect the ends of the label when the jaws are depressed, means for moving the said folding members in the relative direction of the plane of the label length to co- 95 operate with said fold form to complete the formation of the end folds of the label, and means for creasing and expelling the label, as described.
- In testimony whereof I have hereunto set 100 my hand in presence of the subscribing witnesses.
